MOLDED PACKAGING TRAY FOR MEAT
OR THE LIKE

Richard F. Reifers, New Canaan, Conn., and Kenneth D. Bixler, Huntington, N.Y., assignors to Diamond International Corporation, New York, N.Y.

Filed Jan. 27, 1971, Ser. No. 110,365

Term of patent 14 years

Int. Cl. D9—03

U.S. Cl. D9—219

FIG. 3

FIG. 2

FIG. 1

FIG. 1 is a perspective view of a molded packaging tray for meat or the like showing our new design;

FIG. 2 is a front elevation view; and

FIG. 3 is a bottom plan view.

The characteristic feature of the design resides in the inverted V-shaped ribs forming the open-window bottom in combination with the bulged or fluted indentations in the side walls into which the inverted V-shaped ribs merge, and the shape and arrangement of the open windows, as shown.

We claim:

The ornamental design for a molded packaging tray for meat or the like, as shown and described.
